DEVICE FOR INTRODUCING LIQUIDS INTO
PRESSURE VESSELS

Lee S. Twomey, Vista, Calif.

Application July 28, 1936, Serial No. 93,045

10 Claims. (Cl. 122—451)

This application is a continuation in part of my copending application Serial Number 750,164, filed October 26, 1934 under the same title.

An object of my invention is to provide means and methods for introducing a liquid into a vessel containing vapors of the same liquid at relatively high superatmospheric pressure, as for example, the supplying of feed water to a high pressure boiler or the introduction of a low temperature, low pressure liquefied gas into a closed vessel containing liquefied gas and its vapor at a higher pressure.

The rationale and advantages of the invention will be evident on inspection of the attached drawing and the following description thereof in which Fig. 1 diagrammatically illustrates one form of the assembled device and

Fig. 2 illustrates in larger scale a modified form of the bubbler plates of Fig. 1.

For illustrative purposes and without in any wise limiting the application of the device or method, I will first describe their use in connection with feeding water at 80° C. into a steam boiler maintained at 50 atmospheres absolute pressure.

Referring to the drawing, Fig. 1, B and C are pressure vessels which may be of the same size. A is a receiver containing the supply of feed water at 80° C. A may, for example, be the hot well of a condensing system, or it may be any source of supply of water at 80° C. The vessels B and C may be placed at any desired level relative to each other and to the boiler D.

A steam boiler of the water tube type is indicated at D. This consists of a drum 10, water legs 11 and 12 and tubes 13—13, all of which are of conventional design, the water level in the drum being shown at 23. A short connection 14 located on the top of drum 10 establishes communication between the interior of the drum and a space 15 enclosed by a truncated conical member 16, a cylindrical member 17 and a dome 18, to which is attached the steam offtake pipe 19, all being nonleakably joined and of suitable strength to withstand boiler pressure.

A feed water inlet pipe 20 discharges into space 15. Below the point of feed water entry, a perforated bubbler plate 21 extends entirely across space 15, in such manner as to retain above it a pool of feed water, thru which passes steam leaving drum 10 on its way to offtake pipe 19. The steam passing upward thru the perforations is divided into a multiplicity of small streams, insuring intimate contact between steam and feed water, and also preventing the depletion of the

pool thru downward passage of water thru the perforations, altho a limited amount of such water passage does not preclude functioning of the device. The pool of feed water overflows the upper end of downspout 22, which extends thru and above plate 21 a sufficient distance to retain a pool of desired depth. The lower end of pipe 22 extends below the water level 23 of drum 10 or is otherwise water sealed to prevent upward passage of steam thru the pipe.

Instead of the perforated plate 21, a plate or a multiplicity of superimposed plates of other type may be used, as for example those shown in Fig. 2, in which 60 represents a portion of the shell enclosing the space 15 of Fig. 1), 61 and 62 are plates nonleakably attached to 60, extending across the space and provided with steam tubes 63, each of which is surmounted by a cap 64, the lower edge, either smooth or serrated, dipping below the surface of a pool of feed water 20 on the plate. The feed water enters thru pipe 65 above the topmost plate. Two types of water-sealed downspout are shown at 66 and 67, each so located as to cause an approximately maximum travel of feed water across the plates. Instead of the caps of the type shown at 64, any other type designed to cause intimate contact between steam and water may be used. A desirable result, using a simpler device, may be produced by merely causing the steam supply to impinge on plates over which the feed water flows as it enters the boiler.

Returning now to Fig. 1, the space 15 need not be limited to the shape shown. The shape will be dictated by the desire to provide a cheap and simple enclosure for the requisite bubbler plate area, which should be sufficient to allow maximum steam output to bubble thru the pool of feed water without serious entrainment. The uniform distribution of steam flow thruout the plate area 40 may also influence the shape of the enclosure. A plurality of enclosures in parallel may be used if a single enclosure becomes undesirable size.

The pressure vessel B is provided with one or more perforated plates 24, located in its upper portion and adapted to distribute water discharged thereon into a spray falling in B or with one or more spray nozzles or other devices located in its upper portion and adapted to precipitate a spray or rain of water downwardly in B.

The pressure vessel C is provided with one or more bubbler plates 25 located in its upper portion, each provided with water-sealed downspout 26. The plates of Fig. 2 may be substituted for 25 and all statements made above relative to 55

plates, caps, and downspouts in connection with the boiler apply equally to vessel C. Instead of bubbler plates, vessels B and C may each be provided with spray nozzles located near their highest 5 interior points, connected with pipes 27 and 28, respectively, and arranged to cause intimate contact between water entering and steam within the vessels.

Receiver A is connected at its lower point with 10 the suction side of pump 29 by pipe 30 having a stop and regulating valve 31. The discharge side of pump 29 is connected either to vessel B at a point above plate 24 or to the spray nozzles within 15 B, depending on the construction selected. Pipe 27 is provided with a stop valve 32.

The lowest point of vessel B is connected with 20 the suction side of pump 33 by a pipe 34. The discharge side of pump 33 is connected with vessel C at a point above bubbler plate 25 by pipe 28 25 having a stop and regulating valve 35.

The lowest point of vessel C is connected with 30 the suction side of pump 36 by pipe 37. The discharge side of pump 36 is connected with space 15 at a point above bubbler plate 21 by a pipe 29, 25 having a stop valve 38.

The lowest point of vessel B is also connected with the suction side of pump 29 by a pipe 39 having 35 a stop and regulating valve 40. The discharge side of pump 36 is also connected with vessel B at a point above bubbler plate 24, or to spray 40 nozzles within B, by a pipe 41 having a stop and regulating valve 42.

Vessel C is connected at a point at or near 45 its top with space 15 by pipe 43 and pipe 44 having a stop valve 45.

Vessel B is connected, at a point at or near its top with vessel C by pipes 43 and 46, the latter having a stop valve 47.

It is immaterial whether pipe 44 connects with 40 space 15 or with drum 10 above its water line, provided it connects with steam at boiler pressure.

Vessels B and C are provided with vent pipes 48 and 49, having stop valves 50 and 51.

This apparatus is operated in the following 45 manner. First assuming it to be cold (except as to boiler D which is operating under 50 atmospheres steam pressure and receiver A which contains water at 80° C.) and the vessels to be filled with air: All valves being initially closed, valves 50 32, 34, and 50 are opened and pump 29 is started, filling vessel B with 80° water, the air being forced out thru vent 50. At the same time valve 45 is opened allowing steam at boiler pressure to fill vessel C, (displacing air thru vent 51 which is 55 slightly opened for that purpose). Vent valves 50 and 51 are closed as soon as vessels B and C are filled with water and steam respectively.

Valves 32 and 45 are now closed and valves 35 and 47 are opened, allowing the steam pressure 60 in C to equalize on top and bottom of water body in B. The pump 33 now being started, water is drawn from the bottom of B thru pipe 34 and discharged thru plate 25, first forming a pool of water on the plate and thereafter overflowing thru 65 downspout 26. Or, if spray nozzles be used instead of bubbler plates, the water is discharged into C as a spray or multiplicity of small streams. In either event, the steam in C is in large measure 70 condensed, thus reducing the equalized pressure of the two vessels.

Steam flowing out of C thru pipes 43 and 46 to 75 fill the space in B vacated by the water comes into intimate contact with the water entering the top of C, by the action either of the bubbler plates

or of the spray nozzles, and is thereby reduced in temperature and pressure.

Under some conditions, in order to facilitate the attainment of equilibrium between the steam and water, it may be advisable to resort to the 5 following procedure. While water is being pumped from B to C, as above described, water is simultaneously pumped from C to B thru pipe 37, pump 36, pipe 41, and valve 42, the water entering the top of B being either sprayed or 10 flowing over one or more bubbler plates, depending on the construction selected. In this way further contact between water and steam is secured and the operation may be continued as long as desired, provided that the flow from C to B is terminated before that from B to C so 15 that C is finally left filled with water.

After C has been filled with water by either 20 of the alternative methods above described, valves 35 and 41 are closed (also 42 if previously opened), valves 45 and 38 are opened, admitting boiler pressure to both top and bottom of water in C and water is pumped from C thru pipe 37, pump 36, pipe 20, and valve 38 into space 15 at a point above bubbler plate 21, on which it first 25 forms a pool and thereafter overflows downspout 22 and descends to join the body of water in boiler drum 10. Simultaneously, steam from the boiler flows thru pipe 44, valve 45, and pipe 43 into vessel C, which, after all water has been 30 pumped therefrom, is filled with steam at boiler pressure. Valves 38 and 45 are then closed.

The first cycle now being completed, following 35 cycles are conducted in the same manner with the exception of venting the air and with 40 the further exception that under some conditions, in order to facilitate condensation of steam in B by water entering from A, it may be 45 advisable, while pumping from A to B, to simultaneously pump water out thru pipe 39 from the bottom of B, discharging it on top of plate 24 or into the spray nozzles in B, depending on the 50 construction selected. This recirculation may be accomplished by adjusting the relative openings of valves 31 and 40 to regulate ratio of recirculated to newly introduced water to any desired figure, the same pump 29 serving to pump both streams, which are merged at the junction of pipes 30 and 39.

At the time of initiation of any cycle subsequent 55 to the first, the system may, for example, be in the following condition:

Receiver A contains water at 80° C.

Vessel B is filled with steam at 2.1 atm. absolute 60 pressure.

Vessel C is filled with steam at 50 atm. absolute pressure.

Boiler D with steam and water at 50 atm. absolute pressure.

The apparatus illustrated is limited to an intermittent flow of feed water into the boiler. By providing the apparatus (except A and D) in 65 duplicate and correctly timing the functioning of the duplicates, it is possible to produce a continuous flow of feed water to the boiler. It is also obvious that the same result can be obtained by duplicating only the vessels B and C and by so arranging the piping that one set of pumps can serve either set of vessels alternately.

In place of manually operated valves it is both 70 feasible and desirable to use electrically operated valves controlled by suitable timing means or valves operated by means of cams and linkage actuated by any source of power. These devices may readily be so arranged as to reverse 75

the positions of the various valves in the proper sequence and at such intervals as to permit the apparatus to function as above described. Another obvious modification, which is particularly applicable to electrically operated valves, is to make them responsive thru floats and electrical contacts to changes in liquid level; so that the filling or emptying of one vessel initiates the valve settings necessary for the next step. I do not claim these devices, which could be modified over a wide range and which are not part of my invention, but wish it to be understood that by the use of the term "manual" as applied to these valves I do not intend to limit myself to valves actually moved by the hand of an operator.

The number of vessels arranged in series and the pressures described herein are illustrative only. The pressure in vessel B after pumping 20 the water therefrom into C, with any given pressure in the boiler, is reduced by lowering the temperature of the water supplied from A and/or by increasing the number of condensing vessels such as B and C.

25 Receiver A may be replaced by any source of water of desired temperature. If recirculation of water in B is not desired, pump 29 may be dispensed with provided the water in receiver A, or its equivalent just described, is at sufficient pressure to overcome the residual vapor pressure in B; or if this water be under sufficient pressure, the pump may be dispensed with and recirculation retained by the addition of a water operated injector at the junction of pipes 30 35 and 39.

The minimum number of parts is, obviously, one water source, one condensing vessel, one pump, one boiler, and the required pipes and valves, but any greater number of condensing 40 vessels may be used. In case more than two condensing vessels are used, they should preferably consist of one vessel of the type illustrated at B, while the rest should be of the type illustrated at C.

45 It can be seen that by providing the proper number of condensing vessels, the residual steam pressure in the initial vessel can be reduced to any desired value and that if this value is properly chosen, none of the pumps is ever required 50 to pump against any head greater than that of a water column of a height equal to that of a condensing vessel, plus the friction loss in piping and in spray nozzles if used.

In the introduction of feed water into bubbler 55 plates or their equivalent, as in space 15, a small portion of the steam delivered by the boiler is utilized in materially raising the temperature of the feed water, thus reducing thermal stresses in the boiler structure. A further advantage is 60 realized in the removal from the steam supply of a portion of the entrained water particles, the presence of which makes the steam undesirably wet. It will be understood, however, that with the loss of these advantages the water delivered 65 by the train A—B—C may be introduced into the boiler at any level preferred.

When used for feeding boilers, a principal advantage of the apparatus over feed pumps is economy of power, the water being brought to 70 boiler pressure by consumption of heat in elevating the feed water temperature, this being heat that would otherwise be expended in heating the feed water after introduction to the boiler. The only power required for pumping is that used 75 against the extremely low pumping heads de-

scribed above, which are inconsequential compared to boiler pressure, particularly in the case of modern high pressure boilers.

The principles and the apparatus above described may obviously be used for feeding liquefied gases into pressure vessels containing vapors of the same liquid. The only modification required is that all parts of the apparatus will require to be heavily insulated against inflow of atmospheric heat. The temperature and pressure of the final container will be immaterial but the temperature of the liquid in vessel C must not exceed the critical.

If difficulty should be experienced in pumping liquids of extremely low temperature, the vessels 15 through which the introduction is effected may be arranged for gravity flow instead of pumping, as described for the feeding of steam boilers in the copending application.

I claim as my invention:

1. In apparatus for feeding water into steam 20 boilers: a plurality of pressure vessels arranged in series; valved pipes connecting the upper portions of said vessels in series and connecting the upper portion of the last vessel of said series with 25 the steam space of said boiler, and pumping means arranged to move water from each said vessel except the last thereof to the upper portion of the next in the series and from said last vessel into said boiler.

2. A device substantially as and for the purpose set forth in claim 1, including means for returning water from one of said pressure vessels to the upper portion of the next preceding vessel 30 of the series.

3. A device substantially as and for the purpose set forth in claim 1, including means for circulating water from the bottom to the top of one of said vessels.

4. A device substantially as and for the purpose set forth in claim 1, including means in the upper portion of at least one of said vessels for intimately contacting a flow of water with steam initially contained in said vessel, whereby a portion of said steam is condensed.

45 5. Apparatus for introducing liquid from a source of supply at relatively low pressure into a closed receiver containing vapor at relatively high pressure which comprises: a closed pressure vessel; means for introducing said liquid into said 50 vessel and for circulating liquid from the lower to the upper portion of said vessel; means for producing intimate contact between liquid entering said vessel and vapor therein, whereby portions of said vapor are condensed; means for 55 equalizing vapor pressures between said vessel and said receiver, and means for transferring said liquid from said vessel to said receiver.

6. Apparatus for introducing liquid from a source of supply at relatively low pressure into a closed receiver containing vapor at relatively high pressure which comprises: a plurality of closed pressure vessels arranged in series; means for introducing said liquid into the first vessel 60 of said series and for transferring said liquid from each said vessel into the next succeeding vessel of said series and from the last of said vessels into said receiver; means for transferring liquid from at least one of said vessels into a preceding vessel of said series; means for producing intimate contact between the liquid entering each said vessel and vapor therein, whereby 70 portions of said vapor are condensed, and means for equalizing vapor pressures between adjacent 75

- vessels and between said last vessel and said receiver.
7. Apparatus for introducing liquid from a source of supply at relatively low pressure into a closed receiver containing vapor at relatively high pressure which comprises: a plurality of closed pressure vessels arranged in series; means for introducing said liquid into the first vessel of said series and for transferring said liquid from each said vessel into the next succeeding vessel of said series and from the last of said vessels into said receiver; means for transferring liquid from the lower part to the upper part of at least one vessel of said series; means for producing intimate contact between the liquid entering each said vessel and vapor therein, whereby portions of said vapor are condensed, and means for equalizing vapor pressures between adjacent vessels and between said last vessel and said receiver.
8. The method of introducing liquid into a closed receiver containing vapor at relatively high pressure which comprises: establishing a supply of said liquid in a closed vessel under relatively low pressure; establishing vapor communication between said vessel and said receiver

and thereby equalizing the pressures therein; transferring said liquid from said vessel into said receiver and simultaneously substantially lowering the equalized pressure by condensing a material portion of said vapor within the closed system comprising said vessel and said receiver. 5

9. The method of introducing liquid into a closed receiver containing vapor at relatively high pressure which comprises: establishing a supply of said liquid in a closed vessel under a 10 relatively low pressure; establishing vapor communication between said vessel and said receiver and thereby equalizing the pressures therein; circulating a stream of said liquid within a closed system comprising said vessel and said receiver, 15 and thereby lowering the pressure within said system by condensing a material proportion of said vapor.

10. A method substantially as and for the purpose set forth in claim 9, in which said circulating liquid is repeatedly and intimately contacted with said vapor and the condensation of said vapor is thereby accelerated. 20
